UNITED STATES PATENT OFFICE

DAVID ARTHUR WILLIAMS, OF REPRESA, CALIFORNIA, ASSIGNOR OF ONE-HALF TO CHARLES MURRAY, OF REPRESA, CALIFORNIA.

BOTTLE SEAL AND CLOSURE.

No. 916,814.

Specification of Letters Patent. Patented March 30, 1909.

Application filed June 6, 1908. Serial No. 437,127.

To all whom it may concern:

Be it known that I, DAVID ARTHUR WILLIAMS, a citizen of the United States, and a resident of Represa, in the county of Sacramento and State of California, have invented a new and Improved Bottle Seal and Closure, of which the following is a full, clear, and exact description.

This invention relates to certain improvements in means for closing and sealing bottles, so that they cannot be opened without breaking or cutting the seal.

The object of the invention is to provide a casing for covering the entire bottle, the upper portion of the casing forming a sealing cap covering the cork and holding the latter in place. The cap is so secured to the bottle neck that it cannot be removed without breaking the bottle or cutting the cap, and the cap is so secured to the cork that upon the cutting of the former, the cork and separated portion of the cap may be removed together.

Reference is to be had to the accompanying drawings, forming a part of this specification, in which similar characters of reference indicate corresponding parts in all the figures, and in which—

Figure 1 is a side elevation of a bottle constructed in accordance with my invention, having a portion of the inclosing casing broken away; Fig. 2 is a central longitudinal section through the bottle neck and cap; and Fig. 3 is a section similar to Fig. 2, but showing the cork and a portion of the cap removed from the bottle.

My improved bottle may be of any suitable shape or formed of any suitable material, but is preferably of glass and formed with a body portion 10 and a neck 11 of reduced diameter. The outer surface of the neck is provided with two annular grooves 12 and 13, spaced a short distance apart and adjacent the mouth of the bottle. Otherwise, the bottle resembles ordinary bottles commonly found on the market.

After filling the bottle, the mouth is closed by a cork or other suitable stopper 14 entering a short distance into the mouth of the bottle and having an annular flange 15 disposed adjacent the outer surface of the bottle mouth. The entire bottle is inclosed with a sheet metal casing, preferably of aluminum and so formed as to follow the contour of the bottle. The body portion 16

of the casing, and, if desired, a portion of the neck 17 thereof, may be longitudinally fluted or corrugated, so as to give an added protection to the glass of the bottle and prevent it from being broken by blows against the outer surface of the casing. Adjacent the annular groove 13 of the bottle, the casing neck is provided with an outwardly-extending bead 18, forming a groove in the inner surface of the casing neck, and adjacent the groove 12 of the bottle is an inwardly-directed bead 19 in the casing. At the extreme end of the casing is an outwardly-extending bead 20, forming a groove in the inner surface of the casing, for the reception of the annular flange 15 of the cork. The casing extends across the top of the cork and the latter is firmly secured in place by sealing wax 21, or other suitable material, disposed intermediate the top of the cork 14 and the top 22 of the casing.

In assembling the parts after the bottle is filled, the cork 14 is secured within the top of the casing and the bottle is inserted into the casing from the lower end thereof. The bottle and casing are forced together until the cork enters the bottle and the bead 19 of the casing enters the groove 12 of the bottle neck. Sealing wax, pewter, or other suitable material is then poured through an opening 23 in the bead 18, so as to fill the annular space between the bead and the groove 13 and form a locking collar 24, positively preventing the removal of the bottle from the casing. The bottle can now be opened only by cutting away the upper portion of the casing, which may be readily done when it is desired to open the bottle, but after it is once opened, it cannot be reclosed without leaving evidence of the fact that the bottle has been opened.

Instead of providing the opening 23 for the insertion of the sealing wax, pewter, or other sealing material, the bottle may be inverted and the sealing material poured in at the bottom of one or more of the flutes or corrugations. In this case, any sealing material that cools before it reaches the bead 18, will additionally serve for locking the bottle and casing together. To open the bottle, I preferably cut the cap adjacent the mouth of the bottle and beneath the flange 15 of the casing, so that upon removing the top 22 of the casing, the cork will also be removed and carried by said top.

Any suitable means may be provided for cutting the cap, but I preferably provide a wire 25, encircling the casing below the bead 20 and having two or more sharp cutting points 26. The wire is provided with outwardly-extending portions 27, whereby it may be pressed upward against the under side of the flange and may be rotated to cut the flange.

10 By the use of my invention, the wines and other liquids which are to be dispensed, may be put up in very attractive form, as the casing may bear any suitable ornamentation. The bottle may be of the very cheapest material, as it is concealed within the casing and any imperfections will not be visible. The casing protects the bottle during shipment, particularly if the casing is corrugated or fluted, and the casing cannot be removed 15 without the knowledge of such removal being imparted upon a mere cursory examination of the bottle.

16 The bead 19, which enters the groove 12, not only serves to hold the bottle and casing together, but also prevents any of the sealing material which is inserted through the opening 23, from passing upward into engagement with the flange of the cork or the mouth of the bottle. Thus, when the bottle 20 is opened, none of the sealing material will be visible.

Having thus described my invention, I claim as new and desire to secure by Letters Patent:

35 1. A bottle having a substantially cylindrical body and a substantially cylindrical neck of smaller diameter than said body and provided with an annular groove in its outer surface, a sheet metal casing inclosing said 40 bottle, a portion of said casing conforming to the body of said bottle, a second portion

of said casing conforming to the neck of said bottle and having an outwardly-extending bead oppositely disposed to said groove, said bead having an opening therein, and a 45 third portion of said casing forming a cap covering the mouth of the bottle and having an outwardly-extending bead above the mouth of the bottle, a sealing material filling the outer space between said groove and said 50 first-mentioned bead, and a closure within the mouth of said bottle and having an annular flange extending into said second mentioned bead, said cap portion being integral with said neck portion and separable 55 therefrom and carrying said closure.

2. A bottle having a substantially cylindrical body and a substantially cylindrical neck of reduced diameter, a casing inclosing said bottle and having a body portion conforming to the body of said bottle and a neck portion conforming to the neck of said bottle and having a cap portion covering the mouth of said bottle, said cap portion being provided with an outwardly-extending 60 bead above the mouth of the bottle, a closure within the mouth of the bottle and having an annular flange extending into said bead, the said cap portion being integral with said neck portion and separable therefrom 65 and carrying said closure, and means intermediate the ends of the neck portion of said casing for preventing longitudinal movement thereof in respect to the bottle.

In testimony whereof I have signed my 70 name to this specification in the presence of two subscribing witnesses.

DAVID ARTHUR WILLIAMS.
